UNITED STATES PATENT OFFICE.

HARRY LYON, OF HOLBROOK, MASSACHUSETTS, ASSIGNOR TO PERLEY E. BARBOUR,
OF QUINCY, MASSACHUSETTS.

BEADED WELTING.

Application filed October 7, 1925. Serial No. 61,063.

This invention relates to welting of that type which is provided with a longitudinally extending bead on its upper face constructed to engage the shoe upper. More particularly 5 this invention relates to the construction of a relatively light weight welt particularly suitable for women's shoes. A leather welt should be composed largely of flesh stock to be of the required strength, but it is also desirable that its upper face be of grain stock 10 to present the proper finish. Leather stock of the proper thickness for welting for men's shoes is better suited for the manufacture of welting for women's shoes than is the thinner 15 grades of grain leather.

According to one form of this invention, therefore, this heavier stock is utilized to form a beaded welt of the lighter weight desirable for women's shoes by removing stock 20 from between the upper and lower, or side faces of a rectangular welt strip by cutting inward from the edges on either side of the material that will form the bead portion and then bending down and fixing the surface 25 layer on the remaining material either with or without entirely severing this surface layer from the stock. In either case the bead is formed by the stock left when the marginal portions are removed forming a solid, longitudinal core strip integral with the base material, this core strip being surfaced by the 30 completely or incompletely severed grain surface layer.

For a more complete understanding of this 35 invention reference may be had to the accompanying drawings in which

Figure 1 is a cross section through the blank strip.

Figure 2 is a similar view showing one manner 40 in which the blank may be cut preparatory to completing the welt.

Figure 3 is a similar view showing the completed welt.

Figures 4 and 5 illustrate another manner 45 of cutting the welt blank.

Figure 6 illustrates the completed welt made up from the cutting method shown in Figures 4 and 5.

Referring to these drawings, Figure 1 50 shows a substantially rectangular strip of material 1 of the thickness ordinarily used for the preparation of welting for men's shoes. This strip, according to this invention, is

cut away along each margin between its upper and lower or side faces, as shown at 3 and 55 4 in Figure 2, and in its lower face there may be formed an inseam stitch-receiving groove 5. The portions 3 and 4 that are removed leave a base portion of substantially 60 rectangular cross section 6 having between its side edges an integral longitudinal, solid, upstanding rib or core portion 7 to which is integrally fixed an intermediate portion of a surfacing layer 8 of grain stock, the core and 65 the base both being of flesh stock. This core 7 may be of any desired cross section, but as shown its outer edge 9 is substantially perpendicular to the upper and lower faces of the blank and its inner edge 10 is inclined thereto. Next the portions 11 and 12 of the 70 surfacing layer are brought down over the surface of the core strip 7 and fixed thereto and to the upper surfaces of the base portion 6 on either side thereof forming thinned edge 75 portions and a thicker intermediate rib portion and, if desired, the base portion may be trimmed off along opposite sides substantially even with the edges 13 and 14 of this strip 8 before being sewed into a shoe as shown by dotted lines in Figure 3.

Instead of forming the core strip and surface layer integral, the surface layer may be entirely severed from the stock, as shown in Figure 4, to form a separate layer 20. The remaining material 21 is then cut inwardly 85 from the edges as before, portions being removed from one face on either side to form a central core portion 22 similar to the core 7 of the form first described and a stitch-receiving groove 5 may be formed in its opposite face. The surfacing layer is then re-applied to cover over the core portion 22 and the upper face of the base strip on either side thereof as shown in Figure 6. This base strip may then be trimmed off along the outer margins of the cover strip as shown by the dotted lines in Figure 6 to form the completed welt.

Of course, if desired, a surfacing layer of upper stock or any other suitable material could be substituted for the surfacing layer 100 20. It is also evident that the bead could be formed at the extreme inner edge of the welt, if desired, in which case the core strip might be formed by cutting the base material away inwardly at one edge only.

Having thus described certain embodi-

ments of this invention it will be evident to those skilled in the art that various changes and modifications might be made therein without departing from its spirit or scope as defined by the appended claims.

I claim:

1. The method of forming a welt which comprises removing portions inwardly from the edges from a blank strip between its side faces to leave a core strip portion between said edges and faces and fixing together the material on opposite sides of said removed portions to form a strip having thinned edge portions and an intermediate thickened rib.
- 10 2. The method of forming a welt which comprises removing portions inwardly from the edges from a blank strip between its side faces to leave a core strip portion between said edges and faces and fixing together the material on opposite sides of said removed portions to form a strip having thinned edge portions and an intermediate thickened rib extending along one face thereof.
- 20 3. The method of forming a welt which comprises cutting off a thin layer from one face thereof, cutting portions from the remainder along its margins to form a longitudinally extending rib between its edges, and then replacing said cut layer and fixing it to said rib and to the surfaces adjacent thereto.
- 25 4. The method of forming a welt which comprises removing a portion of the longitudinal margin of a welt strip to form a thinned edge portion and a thicker narrow, solid rib portion, and applying to said strip a surfacing layer.
- 35 5. A welt strip comprising a base having a narrow, solid rib integral with and projecting from one face thereof, and a thin sur-

facing layer overlying and fixed to said rib and the adjacent face of said base.

6. A leather welt comprising a base portion of flesh stock having a narrow, solid rib integral with and projecting from one face 45 thereof, and a thin surfacing layer of grain stock overlying and fixed to said rib and to the adjacent face of said base.

7. A welt strip characterized by a face having two margins in substantially the same 50 plane and a longitudinal, solid rib projecting therebetween and integral with said face, and a surfacing layer of grain stock about said rib and extending outwardly from each side thereof.

8. A welt strip characterized by a face having two margins in substantially the same plane and a longitudinal, solid rib projecting therebetween and integral with said face, and a surfacing layer of grain stock secured to 60 the entire surface of said rib and to the adjacent margins of the strip.

9. The method of forming ribbed welting from rectangular welt strips which comprises removing a portion of the stock that lies below the grain along both longitudinal margins of said strip but leaving a thicker solid rib-portion therebetween, and resurfacing said thinned margins with a layer of grain stock.

10. The method of forming ribbed welting which comprises removing a portion of the longitudinal margin of a welt strip that lies below the grain surface thereof by a shoulder-cut which leaves an adjoining thicker portion, and resurfacing said thinned margin with a layer of grain stock.

In testimony whereof I have affixed my signature.

HARRY LYON.
